Primary Examiner — Nathan M Johnston(74) *Attorney, Agent, or Firm* — The Roy Gross Law Firm, LLC; Roy Gross(57) **CLAIM**

I claim the ornamental design for a jewelry organizer, as shown and described.

DESCRIPTION

FIG. 1 is a Perspective view of a jewelry organizer showing my new design;

FIG. 2 is a Back Folded Perspective view thereof;

FIG. 3 is a Front view thereof;

FIG. 4 is a Rear view thereof;

FIG. 5 is a Right-side view thereof;

FIG. 6 is a Left-side view thereof;

FIG. 7 is a Top view thereof; and,

FIG. 8 is a Bottom view thereof.

The broken lines are for the purpose of illustrating portions of the article that form no part of the claim.

1 Claim, 7 Drawing Sheets(56)
